UNITED STATES PATENT OFFICE.

GRAEFF MILLER, OF RIDGEWOOD, NEW JERSEY.

DESIGN FOR A FACE-POWDER BOX.

Application filed March 24, 1925. Serial No. 12,862. Term of patent 14 years.

To all whom it may concern:

Be it known that I, GRAEFF MILLER, a citizen of the United States, and a resident of Ridgewood, county of Bergen, and State of New Jersey, have invented a new, original, and ornamental Design for a Face-Powder Box, of which the following is a specification, reference being had to the accompanying drawing, forming a part thereof.

In the drawings the figure represents a perspective view of a face powder box.

I claim:

The ornamental design for a face powder box as shown.

GRAEFF MILLER.
